CLAIM

The ornamental design for a combined fixed blade knife and sheath, as shown.

DESCRIPTION

FIG. 1 is a front perspective view of a combined fixed blade knife and sheath, showing our new design;

FIG. 2 is an exploded view, the opposite side of the knife being a mirror image of the side shown;

FIG. 3 is a rear elevational view of the combined fixed blade knife and sheath;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
